(57) **CLAIM**

The ornamental design for a sequencing or sample preparation instrument, as shown and described.

DESCRIPTION

FIG. 1 is a top perspective view of a sequencing or sample preparation instrument in accordance with the present invention.

FIG. 2 is a bottom perspective view thereof.

FIG. 3 is front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines immediately adjacent the claimed areas represent the bounds of the claim, while all other broken lines are directed to environment and are for illustrative purposes only; the broken lines form no part of the claimed design.

1 Claim, 6 Drawing Sheets
